(57) **CLAIM**

The ornamental design for a hem bar applied to a window treatment, as shown and described.

DESCRIPTION

FIG. 1 is a perspective view of a hem bar applied to a window treatment showing my new design;

FIG. 2 is a perspective view thereof in an alternate environment;

FIG. 3 is a front view thereof;

FIG. 4 is a rear view thereof;

FIG. 5 is a top view thereof;

FIG. 6 is a bottom view thereof;

FIG. 7 is a left side view thereof;

FIG. 8 is a right side view thereof;

FIG. 9 is a perspective view of a second embodiment thereof;

FIG. 10 is a perspective view thereof in an alternate environment;

FIG. 11 is a front view thereof;

FIG. 12 is a rear view thereof;

FIG. 13 is a top view thereof;

FIG. 14 is a bottom view thereof;

FIG. 15 is a left side view thereof; and,

FIG. 16 is a right side view thereof.

The dashed broken lines depicting a roller blind represent environment that forms no part of the claim. All other dashed broken lines depict portions of the hem bar applied to a window treatment that form no part of the claim.

The break lines shown in FIGS. 9-14 symbolize breaks in the length of the article in which the claimed design is embodied. The appearance of any portion of the article between the break lines forms no part of the claimed design.
